describing the combination of like a shirt and collar
member having a downwardly extending
collar points, the upper portion being adapted to receive
the point of a headed straight pin, the lower portion
being formed with a downwardly extending
collar points, the upper portion being adapted to receive
the point of a headed straight pin, and the
lower portion being formed with a downwardly
extending collar points.

UNITED STATES PATENT OFFICE

2,384,788

COLLAR CLIP

David Bakerman, West Haven, Conn.

Application February 5, 1944, Serial No. 521,165

1 Claim. (Cl. 24—110)

This invention relates to new and useful improvements in a collar clip.

More specifically, the invention proposes the construction of collar clips adapted to be used for attaching the points of a soft collar to a shirt front in a manner to prevent the points from projecting upwards.

Still further the collar clip is characterized by a headed straight pin engageable through the point of a collar and through the front of a shirt to receive a socket fastener member upon the inside of the shirt in a manner to retain the pin in its position extended through the collar point and shirt.

It is a further object of the invention to decorate the front face of the headed pin to improve the appearance thereof.

It is another object of the invention to construct the socket member in a particular manner to permit its complete disengagement from the pin when removing the collar clip.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a partial front elevational view of a shirt provided with collar clips in accordance with this invention.

Fig. 2 is an enlarged partial vertical sectional view taken on the line 2—2 of Fig. 1.

Fig. 3 is a perspective view of the headed straight pin, per se.

Fig. 4 is a perspective view of the socket fastening member, per se.

Fig. 5 is a side elevational view of a collar clip constructed in accordance with a modification of this invention.

Fig. 6 is an enlarged vertical sectional view of Fig. 5.

Fig. 7 is a vertical sectional view taken on the line 7—7 of Fig. 5.

The collar clip, according to this invention, is to be used in combination with a shirt 10 having a soft collar 11 formed with downwardly projecting collar points.

The collar clip includes a headed straight pin 12 consisting of a head 13 and a pin portion 14 which is adapted to be engaged through the point of the collar and through the front of the shirt. A socket fastener member 15 is adapted to be

engaged on the end of the pin at the back of the front of the shirt 10 to retain the headed straight pin 12 in its engaged position with the point of the collar 11 and the front of the shirt 10.

5 The exposed face of the head 13 of the headed straight pin 12 is provided with decorative material 16 which improves the appearance thereof. With the collar clips in the position shown in Figs. 1 and 2 the points of the collar 11 will be 10 retained in their downwardly extended position and will be prevented from projecting upwards. To remove the collar clips it is merely necessary to pull the socket fastening member 15 off the end of the pin portion 14, permitting the pin portion to be withdrawn from the collar point 11 and the shirt 10.

In the modification of the invention disclosed in Figs. 5-7 the construction of the collar clip is similar to that previously described, except for 20 the construction of the socket fastener member 15'. In this form of the invention the socket fastener member 15' includes a hollow casing 17 formed with an opening 18 into which the pin portion 14 of the headed straight pin 12 is adapted 25 to be engaged. The pin portion 14 is formed with a reduced area 19 which is adapted to be engaged by a pair of oppositely disposed fingers 20 of resilient construction which are mounted within the hollow casing 17. As shown in Fig. 6 the fingers 20 engage the pin at the reduced area 19 and act to securely retain it in position with the socket fastener member 15'. The finger portions 20 have operating rods 21 extended in opposite directions and projected from the tubular casing 17, permitting them to be manually 30 squeezed together to spread the finger portions 20 and disengage them from the reduced area 19 and permit the headed pin to be disengaged from the socket fastener member 15'. In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A collar clip having a headed straight pin formed with a reduced area adjacent its point

for engaging through a collar point and adjacent area of a shirt and upon the free end of which a hollow socket member is engaged having internal finger portions engaging said reduced area holding said socket member in position on said pin, said finger portions being resilient to attain and maintain an engaged position with said reduced portion, and means for spreading said

finger portions to disengage them from said reduced portions freeing said socket member to be removed from said pin, comprising operator rods extending in opposite directions from said finger portions to the exterior of said socket member to be manually pressed inwards to spread said finger portions.

DAVID BAKERMAN.
